UNITED STATES PATENT OFFICE.

RAYMOND G. LAWRY, OF CHICAGO, ILLINOIS, ASSIGNOR TO ROBERTS & SCHAEFER COMPANY, OF CHICAGO, ILLINOIS, A CORPORATION OF ILLINOIS.

PROCESS OF SCREENING COAL.

Application filed March 4, 1920. Serial No. 363,157.

To all whom it may concern:

Be it known that I, RAYMOND G. LAWRY, a citizen of the United States, residing at Chicago, in the county of Cook and State of Illinois, have invented a certain new and useful Improvement in Processes of Screening Coal, of which the following is a specification.

My invention relates to a method of, and 10 apparatus for handling coal and has for one object to provide an apparatus in which the impurities are removed from the coal while the coal is being screened and separated according to size and then delivered according 15 to size into a divided weighing hopper from which it then may be directly discharged into the railroad cars.

As the coal comes from the mine it is dumped directly into my apparatus and the 20 processes of the removing of the impurities, screening and weighing the coal are all carried out as parts of one operation. By this method I am able to weigh the coal without impurities and to accomplish the screening, 25 picking, and weighing in an exceedingly simple manner.

My invention is illustrated more or less diagrammatically in the accompanying drawings, wherein,

30 Figure 1 is a vertical section of one part of my apparatus:

Figure 2 is a vertical section of a connecting part of the apparatus:

Figure 3 is a plan view of a part of the 35 screen with parts broken away:

Figure 4 is a plan view of the weighing hopper and the discharge end of the screen chute:

Figure 5 is a vertical section on the line 40 5-5 of Figure 2:

Figure 6 is a horizontal section on the line 6-6 of Figure 5.

Like parts are designated by like characters throughout:

45 A is a hopper into which the coal is dumped. It is provided with a discharge port, A¹, through which the coal is deposited upon the open surface B¹ of the reciprocating screen B. This screen is mounted upon 50 rollers B²-B² and is reciprocated by the mechanism B³. The upper screen B¹ is provided with holes of suitable dimension to allow the slack coal to pass through to the

lower surface C of the screen. C¹ is a port through which the slack coal passes from the level C to the lower level C². B⁴ is an imperforate space in the upper screen B¹ extending over the port C¹. Beyond this space B⁴ the screen B¹ is perforated as at B⁵. These perforations are of such size as to allow the nut coal to pass through on to the level C³. D is an incline joining the upper level of the screen B¹ with the lower level C³ down which the lump coal will pass. D¹ is a baffle plate situated upon the upper level and adapted to deflect the lump coal to the left. D² is a baffle plate situated upon the level C³ and adapted to deflect the nut coal to the right. D³ is a partition on the level C³ and adapted to separate the lump 70 and nut coal which after passing the incline D are upon the same level. E is the discharge end of the screen and is divided into the three discharge openings, E¹ on the level C², and E² and E³ on the level C³. 75

F is a three part weighing hopper divided into the three compartments G, into which the discharge opening E² is adapted to discharge the nut coal, H, into which the discharge opening E³ is adapted to discharge the lump coal, I, into which the discharge opening E¹ is adapted to discharge the slack coal. This hopper F is hung as a unit from the frame F¹ by means of the rods F²-F², and by means of the rods J²-J² is connected with the weighing mechanism K by means of which the hopper load may be weighed as a unit.

Each of the hopper compartments is provided with a discharge opening, respectively G¹, H¹, and I¹. These openings are adapted to discharge the coal into railroad cars which are of course normally upon tracks below the hopper.

J-J are swinging gates, one of which is positioned in the bottom of each of the subdivisions of the weighing hopper. In construction and operation they are identical and I shall, therefore, describe but one.

The gate J is pivoted on the side wall of the hopper subdivision as at J¹. A lever arm K is pivoted on or near the bottom of the hopper subdivision and constitutes a U-shaped member extending about the bottom of the hopper. L is a rod mounted in the member K as at L¹. Pivoted upon it are the

toggle arms M—M. They are so pivoted upon the gate J as at M¹—M¹. On the side of the hopper are the stops N—N, against which the member K will normally rest.

5 Mounted on the member K is the rod O to the lower end of which is adjustably secured the weight O¹ which is adapted to assist in closing the gate. To the upper end of this rod O is secured a rope or cable P. The 10 cables P—P, from the several doors, are brought together at a point convenient for the operator so that the several gates may be simultaneously opened so as to simultaneously discharge their contents.

15 Where in the specifications and claims I have used the expression "to screen," I mean, of course, the ordinary process of separating coal into classes according to its size by means of the screen. Where I have used the 20 expression "picking," I mean, of course, the process of removing the slate and matters of similar nature from the coal.

Although I have illustrated an operative device still many changes both in form and 25 size and shape of parts might be made without departing materially from the spirit of my invention, and I wish, therefore, that my drawings be taken as in a sense diagrammatic.

30 The use and operation of my invention are as follows:

The mine car as it comes from the mine is dumped into the hopper above the screening machine. From this hopper the coal is deposited upon the open surface of an oscillating screen. Some of the coal, preferably 35 the slack, will pass through the screen at this point and will be conveyed forward upon the lower level to the point where it is dumped into the slack division of the 40 weighing hopper. The rest of the coal is conveyed forward and passed upon a screen with larger perforations, and some of it, preferably the nut coal, is screened through 45 and fed forward upon the lower level. Thus the coal has been divided according to size into three grades. After the coal has passed over the last perforated area, that on the upper surface, namely, the lump, is 50 diverted to the left of the screen and down an incline. The nut coal is diverted to the right of the screen. Thus these two grades of coal are brought out upon the same level of the screen but they are separated by the 55 partition in the upper level of the screen at this point.

The coal is then continuously fed forward and discharged into the proper subdivisions of the weighing hopper. During this screening operation and particularly during the latter part of it the coal is picked and impurities are removed from it before it is discharged into the weighing hopper.

When all of the coal from a given mine 60 car has been picked, screened, and deposited

in the hopper the whole is weighed and this operation may be completed and the hopper discharged into the railroad cars beneath it before the coal from the next mine car has passed off of the screen.

It is to be understood of course, that the gates of the various subdivisions of the weighing hopper are normally adapted to be opened simultaneously in order that the hopper may be emptied as a unit. It would 75 of course, be possible to vary this arrangement, but it is generally preferable to have it as above indicated.

I claim:

1. The process of treating a given quantity of coal which consists in separating the coal into two or more classes then removing the impurities from the coal and weighing the entire quantity of coal as a unit minus the impurities.

2. The process of treating a given quantity of coal which consists in separating the coal into two or more classes, conveying such separated coal laterally from the point of operation, removing the impurities from the coal during such conveying movement and then weighing the entire remaining quantity of coal as a unit.

3. The process of treating a given quantity of coal which consists in separating the coal into two or more streams according to size moving said streams laterally, exposing two or more of such streams simultaneously for picking and subsequently associating all of said streams and weighing said coal as a 100 unit.

4. The process of treating a given quantity of coal which consists in separating the coal into two or more streams according to size, moving said streams laterally exposing 105 two or more of such streams simultaneously on the same level for picking and subsequently associating all of said streams and weighing said coal as a unit.

5. The process of treating a given quantity of coal which consists in dividing it into a plurality of streams certain of which streams contain substantially all of the impurities in said coal and certain of which are substantially free from impurities, then 110 moving all of said streams laterally exposing the streams which contain impurities simultaneously for picking subsequently associating all of said streams and weighing the entire amount of said picked coal as a 115 unit.

6. The process of treating a given quantity of coal which consists in dividing it into a plurality of streams certain of which streams contain substantially all of the impurities in said coal and certain of which are substantially free from impurities, then 120 moving all of said streams laterally exposing the streams which contain impurities simultaneously on the same level for pick- 125

ing, subsequently reuniting all of said streams and weighing the entire amount of said coal as a unit.

7. The process of treating a given quantity of coal which consists in dividing it into a plurality of streams certain of which streams contain substantially all of the impurities in said coal and certain of which are substantially free from impurities, conveying all of said streams laterally diverting the stream which is substantially free from impurities below the streams that contain the impurities, exposing said last mentioned streams simultaneously for picking, subsequently associating all streams and weighing said picked coal as a unit.

8. The process of treating a given quantity of coal which consists in separating the coal into two or more classes then removing the impurities from the coal and weighing the entire quantity of coal as a unit minus the impurities while holding the separate classes of coal distinct from each other.

9. The process of treating a given quantity of coal which consists in separating the coal into two or more classes, conveying such separated coal laterally from the point of operation, removing the impurities from the coal during such conveying movement and then weighing the entire remaining quantity of coal as a unit while holding the separate classes of coal distinct from each other.

10. The process of treating a given quantity of coal which consists in separating the coal into two or more streams according to size moving said streams laterally exposing two or more of such streams simultaneously for picking and subsequently associating all of said streams and weighing said coal as a unit while holding the separate classes of coal distinct from each other.

11. The process of treating a given quantity of coal which consists in dividing it into a plurality of streams certain of which streams contain substantially all of the impurities in said coal and certain of which are substantially free from impurities, then moving all of said streams laterally exposing the streams which contain impurities simultaneously for picking, subsequently associating all of said streams and weighing the entire amount of said picked coal as a unit while holding the separate classes of coal distinct from each other.

12. The process of treating a given quantity of coal which consists in dividing it into a plurality of streams certain of which streams contain substantially all of the impurities in said coal and certain of which are substantially free from impurities, conveying all of said streams laterally diverting the stream which is substantially free from impurities below the streams that contain the impurities, exposing said last mentioned streams simultaneously for picking, subsequently associating all streams and weighing said picked coal as a unit while holding the separate classes of coal distinct from each other.

13. The process of treating a given quantity of coal which consists in dividing it into a plurality of streams certain of which streams contain substantially all of the impurities in said coal and certain of which are substantially free from impurities, conveying all of said streams laterally diverting the stream which is substantially free from impurities below the streams that contain the impurities, exposing said last mentioned streams simultaneously on the same level for picking, subsequently associating all streams and weighing said picked coal as a unit while holding the separate classes of coal distinct from each other.

14. A coal handling apparatus including a forwardly feeding screen means adapted to deposit unseparated coal on one end of said screen, said screen adapted to separate said coal into a plurality of laterally moving streams and means for weighing said streams simultaneously, and adapted to divert two of said streams above a third stream and means for weighing said streams simultaneously.

15. The process of treating a given quantity of coal which consists in separating the coal into two or more classes, conveying such separated coal laterally from the point of operation, removing the impurities from the coal during such conveying movement and then weighing the entire remaining quantity of coal as a unit while holding the separate classes of coal distinct from each other.

Signed at Chicago, county of Cook and State of Illinois, this 17th day of February 1920.

RAYMOND G. LAWRY.
